ELECTRICAL FENCE CHARGING APPARATUS

Norman F. Agnew and Willard P. Place,
Wilkinsburg, Pa.

Application June 6, 1939, Serial No. 277,676

12 Claims. (Cl. 256—10)

Our invention relates to electrical fence charging apparatus and more particularly to apparatus of this character which is safe, reliable and efficient in its operation.

One feature of our invention is the provision of an initial biasing charge on the fence or enclosing conductor which renders the voltage impulses more effective, thus making it possible to decrease the size and cost of the apparatus. Another feature of our invention is that a residual charge is left on the enclosure which provides a measure of protection during a temporary power outage or other interruption of the impulse voltage. A further feature of our invention is the provision of apparatus which may be either manual or automatic or both, for indicating the integrity of the system. A still further advantage of our system is the provision of apparatus for preventing the flow of an excessive short-circuit current in the charged conductor, thus increasing the safety factor of the system. An added advantage is involved in what may be conveniently termed a "trigger" action of the apparatus in that a contact with the charged conductor, though occurring between impulses, causes the immediate discharge of an impulse, thus providing the desired warning shock immediately upon contact with the conductor and making it possible to use fewer impulses per unit of time with a resulting saving in power input. Other objects, features and advantages of the apparatus will become apparent from the description which follows.

We shall describe two forms of electrical fence charging apparatus embodying our invention and shall then point out the novel features thereof in claims.

In the accompanying drawing, Fig. 1 is a diagrammatic view showing one form of electrical fence charging apparatus embodying our invention. Fig. 2 is a diagrammatic view showing a modified form of the apparatus of Fig. 1, also embodying our invention. Figs. 3 and 4 are voltage curves showing certain characteristics of the apparatus of Figs. 1 and 2.

Similar reference characters refer to similar parts in each of the several views.

In apparatus employing a charged circuit for preventing farm stock or other animals from leaving an enclosure, it is desirable to establish a potential sufficiently high to provide the necessary warning shock, yet of such character as to create no damage or undue distress to the animal coming in contact therewith. A further reason for making the charged conductor effective

for its purpose yet comparatively harmless is, of course, the likelihood of accidental contact therewith by children or others. With these and other important considerations in mind, our apparatus is so designed that it delivers a voltage of relatively high instantaneous value, but of comparatively short duration and having very low maximum current intensity. Moreover, the apparatus is so designed and arranged that a failure of any part thereof will not render the apparatus unsafe or hazardous.

Referring first to Fig. 1 of the drawing, the step-up transformer T_1 has a primary winding 4 connected to a suitable source of alternating current (not shown) which may, for example, be the usual 110 volt, 60 cycle commercial source. The secondary winding has a mid-tap which divides the winding into two substantially equal portions 5 and 6 connected respectively to the anode terminals P_1 and P_2 of a suitable full-wave rectifying tube RT . A third winding 7 of transformer T_1 supplies the heating current for the heater element F of the tube.

The output of the tube RT is impressed across a circuit which may be traced from the cathode C , wire 8 , switch arm S_1 , resistors R_1 and R_2 , condenser C_1 , primary winding 9 of impulse transformer T_2 , and wires 10 , 11 and 12 , back to the transformer T_1 and the respective anode terminal P_1 or P_2 . The purpose of condenser C_1 is to enable a higher output voltage to be provided since the condenser is maintained at the crest voltage value delivered by the tube RT . This condenser is not essential, however, and may be dispensed with, if desired. The resistor R_1 is of relatively high value as compared with resistor R_2 , and its purpose as well as the purpose of the switch S_1 will be brought out more fully hereinafter.

Across a portion of the circuit just traced, namely, across resistor R_2 , condenser C_1 and impulse winding 9 , is connected a discharge tube DT_1 which may be of any suitable type, such as a neon or glow discharge tube either with or without a starter anode. The tube DT_1 is designed to have a critical breakdown potential such that after a predetermined charge is supplied over the charging resistor R_1 and is accumulated by the condenser C_1 , the tube will break down and will cause a rapid rush of current in winding 9 , thus inducing a voltage of high peak value and relatively short duration in winding 13 of the impulse transformer T_2 . The ohmic value of the discharge resistor R_2 is quite low as compared with R_1 in order that a substantial amount of energy

may be quickly discharged by the tube into the impulse transformer. If sufficient resistance is present in winding 9 of the impulse transformer, the discharge resistor may be dispensed with.

As soon as a sufficient charge is dissipated from condenser C1 and the tube voltage reaches its critical cut-off value, tube DT1 will cease conducting, thus causing another change in the flux condition of transformer T2 whereby a small reverse impulse will be delivered from winding 13. The constants of resistors R1 and R2, condenser C1, and transformer T2 are so chosen with respect to the characteristics of the tube DT1 as to provide a cyclic charge and discharge operation of condenser C1 and a periodic discharge of tube DT1 at a rate which may, for example, be of the order of 40 times per minute.

The impulse voltage from winding 13 is applied (through condenser C3 and switch arm S3) between the ground wire 14 and the stock enclosing conductor or guard wire 15 which is insulated from ground. The guard wire 15 may be an insulated fence wire or any other suitable stock enclosing conductor or group of conductors exposed to electrical contact by livestock or other enclosed animals, but insulated from the ground. It is apparent therefore that between wire 15 and ground there will recurrently appear sharp impulses of potential whereby an unpleasant shock will be administered to stock coming in contact with the wire. Condenser C3 is of relatively low impedance to the impulse energy and serves to intensify the voltage output by providing a residual or biasing potential which maintains an initial charge on wire 15 at all times and which adds to the potential delivered by the impulse transformer T2. This condenser is charged over a circuit which may be traced from the cathode C of tube RT, through the resistor R5, wire 16, condenser C3 and wires 10, 11, and 12, to the center tap of transformer T1 and one or the other anode of tube RT. In this manner, the peak voltage delivered by the apparatus is substantially increased without requiring a corresponding increase in the voltage capacity of the impulse generating elements of the system. Moreover, by virtue of the presence of the charged condenser C3, the guard conductor 15 will be maintained partially effective even though operation of the impulse generating apparatus may be temporarily interrupted for any reason, such for example, as a failure of the tube DT1.

Referring for the moment to Fig. 4 which shows the general appearance of the voltage impulses which are impressed on wire 15, it will be noted that condenser C3 may be used to provide the bias voltage *a* in the diagram, the impulse transformer being then required to supply only the portion *b* of the resultant voltage *c* which is effective on the charged conductor. The bias *a* may, for example, be of the order of 400 volts, whereas *c* may be of the order of two to three times this value; thus *b* need only be of the order of 400 to 800 volts. The duration of an individual impulse may be of the order of 0.003 second. These values are of course only illustrative and may be widely departed from, in practice.

It will be understood that the voltage diagram of Fig. 4 is not intended to show the voltage and time values to scale, its purpose being largely to aid in providing a more clear understanding of the advantageous effect of condenser C3. The small reverse impulses which occur upon cessation of current flow in the discharge tube have

not been shown in this diagram for simplicity. For a very long fence, or if the conductor 15 has considerable electrostatic capacity to ground, the duration of an impulse will be somewhat longer and it may have a somewhat lower peak value, unless the apparatus is so proportioned as to take care of the increased load represented by the capacity to ground.

Referring again to Fig. 1, the resistor R5 is of relatively high resistance and in normal operation with the guard wire ungrounded, no appreciable potential drop will appear across this resistor. When a ground develops, however, a substantial potential drop will appear across resistor R5 due to the ground leak and this drop may be used to provide an indication of whether or not an excessive ground exists on the charged conductor. The resistor R5 provides a path for the flow of current into condenser C3 and if the insulation of the system is high, the current flowing through the resistor will be comparatively small but will increase substantially should an accidental ground develop, thus establishing the required indication potential. A discharge tube DT2 designed to break down at or below the potential drop effective during the grounded condition but to remain normally non-conducting, may be used across resistor R5 to provide a suitable visual indication of the grounded or ungrounded condition of the charged conductor.

Referring now to the manually operable switch arms S1, S2 and S3, these arms are mechanically connected in such a manner that when arm S1 is moved from its normal or intermediate position 2 to either of its extreme positions 1 or 3, the arms S2 and S3 will be caused to assume corresponding positions. Position 1 is what we shall term the testing position and is provided for the purpose of determining whether the system is in its proper operating condition and no excessive leakage or short-circuit exists between the charged conductor and ground. Switch arm S1 is biased by means of a spring so that it will automatically return to its normal position 2.

When the switch arms occupy the testing position 1, the condenser C1 instead of being charged through the usual charging resistor R1, will now be charged through the ground resistance between wires 14 and 15. The charging path for condenser C1 will now extend from cathode C, wire 8, switch S1 in position 1, wires 17 and 16, ground resistance between wires 15 and 14, switch arm S3 in position 1, resistor R4, wires 20 and 19, resistor R2, condenser C1, winding 9, and wires 10, 11 and 12, to the transformer T1 and anode P1 or P2 of tube RT. Resistor R4 is merely a protective resistor which serves to guard the tube DT1 in the event of a low resistance ground on conductor 15.

If the conductor 15 is well insulated, the effective resistance through which the condenser C1 is charged will have a very high value which will be of about the same order of magnitude as that of the usual charging resistor R1. Accordingly, with the switch arms in position 1 under this condition, the rate at which the tube DT1 will charge and discharge will be about the same as that obtained in normal operation, with the switches in position 2. If, however, a ground is present on wire 15, the rate of charge and discharge will undergo a marked increase, whereupon the tube DT1 will flash rapidly and so will provide a simple and direct visual indication of the grounded condition. By means of the testing provision which we have embodied in our ap-

paratus, it is possible to check the effectiveness of the system periodically in a simple and convenient manner without in any way disturbing the apparatus or its permanent connections.

The purpose of the switch position 3 is to make possible an increase in the strength of the discharge from conductor 15 under certain conditions. We have found from experience that during the training period of the cattle or other livestock, when the charged conductor is first used, it is desirable to administer a somewhat stronger impulse than that which will later suffice, once the animals have learned to approach the conductor with a certain amount of caution. Accordingly we shall term position 3 the "training" position.

When the switch arms occupy the training position 3, the capacity of condenser C2 is added to that of condenser C1 by virtue of switch S2 so that a greater amount of energy is stored and is accordingly discharged through the impulse transformer. The charging resistor R3 which now replaces resistor R1 due to movement of the switch S1 is of lower resistance in order that the increased charge may readily flow into the condensers C1 and C2 in parallel. The greater charge will, of course, increase the energy which is discharged through the impulse transformer, making it possible to intensify the discharge from this transformer so as to render the conductor 15 more effective for its purpose. From oscillographic studies, we have found that the actual increase in open circuit voltage with the switches in the training position 3 is not very great, but there is a marked increase in the short-circuit current, and a smaller decrease in the voltage which remains effective when a given load is connected between the conductor 15 and ground.

Referring again to the biasing condenser C3, we have found that this condenser performs an additional function in that it tends to compensate automatically for changes in the moisture condition of the ground. The amount of surface moisture determines largely the resistance of the contact between an animal and ground and so influences the voltage which is necessary on the charged conductor. When the ground is dry and increased voltage is needed, the insulation of conductor 15 will also be greater because its supporting insulators will then be dry, so that condenser C3 will receive its full charge and will maintain this charge. When, however, the ground is wet and less voltage is required, the insulation resistance of conductor 15 will also be lower, so that condenser C3 will receive less charge and the effective voltage output will be lower. One advantageous result of this arrangement is that the dry weather condition does not make it necessary to increase the energy output of the impulse apparatus. Were it not for the presence of condenser C3, increased energy would have to be stored in condensers C1 and C2 with a resultant increase in the short-circuit current which is obviously undesirable both from an energy as well as a safety standpoint. We have found, for example, that a short-circuit current of the order of 100 milliamperes is ample and the apparatus may be designed with inherent current-limiting features for this purpose. One convenient way of accomplishing this result is to introduce resistance into the impulse transformer windings or introduce high leakage reactance into this transformer, or both.

Referring now to Fig. 2, we have shown in this figure a slightly modified arrangement of the

apparatus of Fig. 1. The chief difference resides in the elimination of resistors R2 and R4, equivalent resistances being introduced into the windings themselves of the impulse transformer T2.

5 A resistor R8 has also been introduced in series with the discharge tube DT2 in order to protect this tube as well as to limit the short-circuit current in the event of tube breakdown and a ground on the charged conductor occurring simultaneously.

10 Except for a slight rearrangement of the circuit of transformer T2 to make the connections more simple and direct, the circuits and operation of the apparatus of Fig. 2 are essentially the same as that of Fig. 1 and need not be repeated in detail. It will be sufficient to say that condenser C1 is charged over the resistor R1 and discharges through the tube DT1 and winding 9, as before. Similarly, the impulse potential generated in winding 13 is added to the potential of condenser C3 so that the resultant peak voltage appears between the charged conductor 15 and ground. The condenser C3 is maintained constantly charged over a similar circuit to that described in connection with Fig. 1. Also, the testing position 1 and training position 3 of the switch arms perform the same functions as previously described. If desired, the filament of the rectifier tube RT may be connected with the cathode by means of the connection 21 to fix the filament potential and this, of course, can also be done in Fig. 1.

15 An important advantage which is present in the apparatus of both Figs. 1 and 2 is that a contact with the charged conductor, though occurring at a time between succeeding impulses, hastens the discharge of the apparatus and acts as a trigger to release the accumulated charge immediately upon contact. This can perhaps be best understood from the voltage diagram of Fig. 3 in which we have attempted to show the results of oscillographic observations pertaining to this particular feature of operation. The underlying reasons for this phenomenon are somewhat complicated and we do not deem it necessary for an understanding of our invention to present these reasons in detail. It will be sufficient to say that a contact with the charged conductor induces a corresponding charge in winding 9 of the impulse transformer T2 which accelerates the discharge of the tube DT1.

20 Assuming, for example, that the conductor 15 is touched at some time such as indicated at d in Fig. 3, in between the usual periodic impulses, we have found that after a small reverse pulse, there follows immediately the main impulse without the necessity for waiting during the usual interval between impulses. This first impulse may or may not have as high a peak as the usual impulses, depending upon how much charge has been accumulated in condenser C1. Succeeding impulses such as g and h will then follow in the usual order and will be timed from the impulse f. Were it not for the "trigger" action of the apparatus, a certain time would elapse between contact with the conductor and the occurrence of the succeeding impulse i, shown dotted in the diagram. This time might be sufficient to enable an animal to escape through the enclosure. To put the matter in another way, this feature of our apparatus makes it possible to space the impulses much farther apart, with a resulting decrease in power input and without any sacrifice in the protective features of the apparatus.

In order to provide a general idea of the relative magnitude of certain constants of the apparatus of Fig. 1, for example, we have found that with an output of about 325 volts delivered from each of the windings 5 and 6 of transformer T1, one set of values of the various condensers and resistors of the apparatus giving satisfactory results may be as follows: condensers C1 and C2, 2 microfarads each; condensers C3 and C4, 0.25 microfarad each; resistors R1, R3 and R5, 0.5 megohm, 0.2 megohm, and 0.1 megohm, respectively; resistor R2, 600 ohms; and resistor R4, 10,000 ohms. For the rectifying tube RT and discharge tube DT1, the tubes designated commercially as 6ZY5G and OA4G, respectively, were found to be suitable. An impulse transformer T2 having a step-up ratio of the order of 7 to 1 was found to be satisfactory.

With apparatus such as above, and switch arms occupying the normal position 2, the peak charge on conductor 15 is of the order of 1000 volts and the bias provided by condenser C3 is of the order of 400 volts. The parts are so proportioned that the maximum current obtainable from the apparatus is well within a safe value so that the apparatus is incapable of administering an injurious shock. This safety feature has been borne out by numerous tests of the apparatus under actual service conditions. The foregoing values may obviously be varied widely to suit the conditions of a particular installation by proper selection of the circuit constants, discharge tubes, transformer ratios, etc., as will be readily apparent to those skilled in the electrical field.

It will be understood that we have set forth certain numerical values solely for the purpose of providing a more clear understanding of the general proportions of the apparatus and not in any limiting sense whatsoever. It will be clear that any or all of these values may be widely changed, as desired, to meet the requirements of a given installation such, for example, as the prevailing value of insulation resistance of conductor 15 to ground, moisture content of the soil in the vicinity of the charged conductor, type of livestock to be herded, etc.

From the foregoing description, it will be apparent that we have provided apparatus which is simple, compact, safe and highly effective in its operation. By eliminating all moving parts, the reliability of the apparatus has been greatly increased whereas the cost as well as the necessity for frequent adjustment and maintenance have been substantially decreased.

Although we have herein shown and described only two forms of apparatus embodying our invention, it is understood that various changes and modifications may be made therein within the scope of the appended claims without departing from the spirit and scope of our invention.

Having thus described our invention, what we claim is:

1. In combination, a source of unidirectional current, a shock administering condenser, a resistor, means for charging said condenser from said source through said resistor, an impulse transformer, a discharge device, means for discharging said condenser through the input winding of said transformer and said discharge device when the accumulated charge on said condenser reaches the breakdown potential of said discharge device, said discharge occurring periodically at a rate determined by the constants of said resistor, said condenser and said discharge

device to thereby induce periodic voltage impulses of sufficiently high peak value for shock purposes in the output winding of said impulse transformer, a bias condenser connected in the output circuit of said transformer, means for charging said bias condenser from said unidirectional source, an enclosing conductor, and means for impressing said voltage impulses augmented by the charge from said bias condenser between said enclosing conductor and ground.

2. Apparatus for providing a stock enclosure by means of a charged conductor comprising, in combination with said conductor, means for producing periodic voltage impulses of sufficiently high peak value for shock purposes, a condenser for providing an initial bias on said conductor, means for maintaining said condenser in a charged condition, and means for impressing said voltage impulses augmented by said initial bias from said condenser between said conductor and ground.

3. Apparatus for providing a stock enclosure by means of a charged conductor comprising, in combination with said conductor, means for producing periodic voltage impulses of relatively high peak value but of relatively low available power, means for maintaining an initial charge upon said conductor, and means for impressing said voltage impulses between said conductor and ground, whereby both said initial charge and said impulses cooperate to increase the effectiveness of said conductor by increasing the peak voltage on the conductor.

4. Apparatus for providing a stock enclosure by means of a charged conductor comprising, in combination, an impulse transformer having its output winding connected with said conductor; means including the input winding of said transformer, a discharge device, and an energy storing device for periodically causing a discharge from said energy storing device through said discharge device and input winding to thereby impress recurrent voltage impulses of relatively high peak value from said output winding on said conductor; an auxiliary energy storing device for providing a bias on said conductor, and means for causing energy to be stored in said auxiliary device, said auxiliary device being connected with said output winding in such manner that contact between said conductor and ground will release energy stored in said auxiliary device through said impulse transformer to thereby accelerate the discharge from said discharge device.

5. In an electrically charged enclosure, in combination, a discharge device coupled inductively with said enclosure for impressing periodic voltage impulses of relatively high peak value on said enclosure, and means including a constantly energized energy storing device for providing a bias on said enclosure, said device being connected with said enclosure in such manner that contact between said enclosure and ground will release energy stored in said constantly energized device, thereby reacting on said discharge device through the inductive coupling so as to cause an acceleration of said impulses.

6. In combination with an electrically charged enclosure, means for providing an initial charge on said enclosure, means for periodically impressing voltage impulses of predetermined power upon said enclosure to cooperate with said initial charge and so to increase the charge on said enclosure, and means for at times increasing the power of said voltage impulses to thereby increase the effectiveness of said enclosure.

7. In combination with an electrically charged enclosure, means for providing an initial charge on said enclosure, means including a discharge device for periodically impressing voltage impulses of predetermined power upon said enclosure to cooperate with said initial charge and so to increase the charge on said enclosure, and means for at times increasing the energy discharged by said discharge device to thereby increase the power of said impulses so as to increase the effectiveness of said enclosure.

8. Apparatus for providing a stock enclosure by means of a charged conductor comprising, in combination, a condenser, a discharge device, a charging resistor, a source of unidirectional current, a circuit closer having a first position in which said condenser is intermittently charged from said source over said resistor to thereby cause a periodic discharge from said device to be impressed upon said conductor, means for at times causing said circuit closer to assume a second position in which said charging resistor is excluded and said condenser is charged from said source through the resistance between said conductor and ground, and means for biasing said circuit closer to said first position.

9. In combination with an enclosing conductor, means for establishing a shocking potential between said conductor and ground, and means including a condenser connected between said conductor and ground for augmenting said shocking potential and for automatically compensating the potential effective on said conductor in accordance with the insulation resistance of said conductor to ground whereby the efficiency of said conductor is maintained both in wet weather and in dry weather.

10. In combination with an enclosing conduc-

tor, a source of current, means for establishing a shocking potential from said source between said conductor and ground, a condenser connected between said conductor and ground, and means for charging said condenser from said source and adding the charge thereof to said shocking potential to thereby increase the magnitude of said potential and to automatically compensate said potential in accordance with the insulation resistance of said conductor to ground, whereby the efficiency of said conductor is maintained both in wet weather and in dry weather.

11. In electric fence charging apparatus including a fence conductor which is charged for providing a stock enclosure, the combination of means for producing periodic voltage impulses of sufficiently high peak value for shock purposes, a condenser for providing an initial bias on the fence, means for maintaining said condenser in a charged condition, and means for impressing said voltage impulses augmented by said initial bias from said condenser between the fence and ground.

12. In electric fence charging apparatus including a fence conductor which is charged for providing a stock enclosure, the combination of means for producing periodic voltage impulses of relatively high peak value but of relatively low available power, means for maintaining an initial charge upon the fence, and means for impressing said voltage impulses between the fence and ground, whereby both said initial charge and said impulses cooperate to increase the effectiveness of the fence by increasing the peak voltage thereon.
